UNITED STATES PATENT OFFICE.

ALBERT J. BLOCK, OF CHICAGO, ILLINOIS. ASSIGNOR TO EL DORADO JONES, OF CHICAGO, ILLINOIS.

ELECTRICALLY-HEATED APPLIANCE.

1,142,769.

Specification of Letters Patent.

Patented June 8, 1915.

Application filed August 22, 1912. Serial No. 716,404.

To all whom it may concern:

Be it known that I, ALBERT J. BLOCK, a citizen of Great Britain, and a resident of Chicago, in the county of Cook, State of Illinois, have invented certain new and useful Improvements in Electrically-Heated Appliances, of which the following is a specification.

This invention relates to electrically heated household implements, and has for its object to provide a simple and efficient structural formation and arrangement of parts in an electrically heated household implement adapting the same for use as a sad or smoothing iron principally, and which is capable of ready utilization as a portable stove, a bread toaster, etc., all as will hereinafter more fully appear.

In the accompanying drawings: Figure 1, is a side elevation illustrating the general arrangement of the present appliance, with an ordinary sad-iron associated therewith. Fig. 2, is a sectional plan view of the same, the sad-iron being removed. Fig. 3, is an inverted plan view of the electric heating unit, with parts broken away to illustrate the internal construction. Fig. 4, is an enlarged longitudinal section on line $x-x$, Fig. 2. Fig. 5, is an enlarged fragmentary section of the heating unit, illustrating the internal construction and terminal connections thereof.

Similar reference numerals indicate like parts in the several views.

Referring to the drawings, 1 represents the flat base or shoe portion of the present appliance of any usual and ordinary configuration and provided with a marginal upturned flange 2 which in the preferred construction as shown in Fig. 4, is formed with internal bearing ledges 3, intermediate the height of said flange, for the attachment and support of the electrical heating unit hereinafter described, and which is disposed in the open top cavity formed by the flange 2, aforesaid.

The electrical heating unit of the present improvement comprises a detail formation and combination of parts, as follows.

4 is an upper carrying plate of a size corresponding with the bearing ledges 3 above described, and adapted to rest thereon

and be attached thereto by screws 5, or other usual attaching means.

6 are a plurality of knobs or protuberances on the upper surface of the plate 4 aforesaid, adapted to support the body of the hereinafter described sad-iron away from extended contact with said plate, and by providing an intervening air space prevent the free passage of heat from the electrical heating unit to said main body of the sad-iron.

7 and 8 are companion sheets or layers of mica or like insulating material disposed on the underside of the aforesaid upper carrying plate 4, and between which sheets or layers a conductor or lead 9 of the electrical heating element 10 is disposed.

11 is a sheet or layer of mica or like insulating material disposed beneath the aforesaid sheet or layer 8, and around which the electrical heating element 10, preferably in the form of a narrow band is wound spirally as illustrated in Fig. 3. 75 One end of said element 10, is attached to the conductor or lead 9 above described, and the other end to a companion conductor or lead 12, as shown.

13 is a sheet or layer of mica or like insulating material disposed beneath the aforesaid sheet or layer 11, and its spirally wound heating element 10, to insulate the same from the protecting shield or plate now to be described.

14 is a plate or shield of metal disposed on the underside of the sheet or layer 13 above described.

The sheets 7, 8, 13 and plate 14 are made of smaller dimensions than the upper carrying plate 4, while the layer sheet 11 is made of still smaller dimensions, so that the edges of the spirally wound electrical heating element 10 will not be exposed at the sides, as illustrated more particularly in Fig. 3.

15 are a plurality of rivets or like fastening means whereby the above described series of plates and sheets 4, 7, 8, 11, 13 and 14, are permanently secured together as a single heating unit, which when disposed in place in the open top cavity of the shoe or base 1 is free from mechanical contact with any part of said shoe or base except

through the before described connection of the carrying plate 4 to said shoe or base.

16 is an integrally formed angular bracket at one end of the carrying plate 4 and extending vertically therefrom, with its upper portion formed into a holding sleeve 17, for receiving the end of the usual flexible conductor 18 by which the appliance is connected to an ordinary fixture or wall socket. In addition to its function of housing the end of the flexible conductor 18, the said bracket is adapted for use as a foot or rest to support the device on its end during periods of temporary non-use.

15 The electrical wires or leads contained in the above mentioned flexible conductor 18, are connected to the conductors or leads 9 and 12 of the electrical heating element 10 in the ordinary manner as illustrated in Fig. 4.

19 is an elastic bail preferably formed by a closely wound spiral of wire, the respective ends of which are connected to suitable eyes, at the sides of the flat shoe or base 1, and approximately midway the length of the same. Said elastic bail is adapted to engage over the body portion of an ordinary sad-iron 20, to hold the same in place in the open top cavity of the base or shoe 1, in proper assembled relation and so that the combined devices may be handled as a single appliance by the handle of the sad-iron, in ordinary ironing or smoothing operation.

21 are a series of lateral orifices formed in the marginal flange 2 of the base or shoe 1, before described. Said orifices are adapted for engagement with prongs on the upper end of any ordinary and suitable form of skeleton support or tripod, when it is desired to support the present appliance in an inverted condition from that shown in Fig. 4, of the drawing, and in a raised position above the top of a table or stand, with a view to utilize the appliance as a bread toaster, or in a kindred use. Said orifices 21 are also adapted to receive similar prongs or a handle or bail, when the appliance is used independent of the ordinary sad-iron above described, for ironing and smoothing purposes.

Having thus fully described my said invention what I claim as new and desire to secure by Letters Patent, is:

1. In an electrically heated appliance, the combination of a base member formed with an upwardly extending marginal flange, an electrical heating element disposed in the lower portion of the cavity formed by said flange; an engaging means carried by said base member, and a manipulating handle adapted for detachable engagement with the aforesaid engaging means of the base member, substantially as set forth.

2. An electrically heated appliance, comprising a flat shoe having an upturned mar-

ginal flange forming an open top cavity, an electrical heating unit detachably secured in said cavity, and an elastic bail secured to said shoe midway the length thereof and adapted for holding engagement with the body portion of a sad-iron, substantially as set forth. 70

3. An electrically heated appliance, comprising a flat shoe having an upturned marginal flange forming an open top cavity, 75 and an electrical heating unit detachably secured in said cavity and having a flat top member formed with a plurality of protuberances on its upper surface, substantially as set forth.

4. An electrically heated appliance, comprising a flat shoe having an upturned marginal flange forming an open top cavity, and an electrical heating unit detachably secured in said cavity and having an integrally formed and angularly disposed bracket at one end, substantially as set forth. 80

5. An electrically heated appliance, comprising a flat shoe having an upturned marginal flange forming an open top cavity, 85 and an electrical heating unit detachably secured in said cavity, the same comprising an upper carrying plate of metal, a lower protecting plate of metal, a series of intermediate sheets of insulating material, and an electrical heating element disposed between said sheets, substantially as set forth. 90

6. An electrically heated appliance, comprising a flat shoe having an upturned marginal flange forming an open top cavity, 100 and an electrical heating unit detachably secured in said cavity, the same comprising an upper carrying plate of metal, a lower protecting plate of metal, a series of intermediate sheets of insulating material, and 105 an electrical heating element disposed between said sheets, the bottom plate and series of intermediate sheets being of smaller dimensions than the upper carrying plate, substantially as set forth. 110

7. An electrically heated appliance, comprising a flat shoe having an upturned marginal flange formed with internal bearing ledges intermediate its height, and an electrical heating unit supported on said bearing ledges in the cavity formed by said flange, said heating unit comprising an upper carrying plate of metal, a lower protecting plate of metal, a series of intermediate sheets of insulating material and 115 an electric heating element disposed between said sheets, substantially as set forth. 115

8. An electrically heated appliance, comprising a flat shoe having an upturned marginal flange formed with internal bearing 120 ledges intermediate its height, and an electrical heating unit supported on said bearing ledges in the cavity formed by said flange, said heating unit comprising an upper carrying plate of metal, a lower pro- 125

tecting plate of metal, a series of intermediate sheets of insulating material and an electrical heating element disposed between said sheets, the lower plate and series 5 of intermediate sheets being of smaller dimensions than the upper carrying plate, substantially as set forth.

Signed at Chicago, Illinois this 17th day of August 1912.

ALBERT J. BLOCK.
